HOOD CATCH

Filed Feb. 10, 1932

UNITED STATES PATENT OFFICE

1,967,587

HOOD CATCH

Raymond G. Moore, Bridgeport, Conn., assignor
to The Bassick Company, Bridgeport, Conn.,
a corporation of Connecticut

Application February 10, 1932, Serial No. 591,948

3 Claims. (Cl. 292—49)

The present invention relates to improvements in hood catches, particularly of the type having catch means interiorly and at each end of the hood, and which are adapted to be operated by a single exteriorly arranged operating handle disposed substantially centrally of the hood, the catch means being in the form of rock-shafts having their axes of rotation longitudinally of the hood and the operating handle being rotatable about an axis disposed transversely of the hood. Heretofore various means have been employed for translating the movement of the operating handle into movement of the catch means, and for the most part these have been complicated, expensive and unsatisfactory, and because of the use of levers, links, etc., necessitated a number of loose connections and pivots which were subject to wear, rattling, and rapid deterioration, and required considerable effort to operate. It is proposed in the present invention to provide movement translating means having few relatively movable parts and in which loose connections, pivots, links etc., are eliminated to a great extent, which may be operated with facility, and which will be efficient and reliable in operation. To this end I propose in the exemplary illustrated embodiment of my invention to provide a relatively large barrel cam rigidly connected to the handle shaft, and engaging a yoke member directly connected to the rock-shaft means of the catch elements.

A further object of the invention is to provide a hood catch which will compensate for irregularities in the mounting of the hood and keeper brackets, and which will automatically equalize the holding pressure of the plurality of catch means, so that the hood will be held uniformly at all points. Another object is to provide a plurality of differentially movable catch elements, and equalizing coupling means in the form of a cam actuated yoke member which will compensate for irregularities that may exist between said elements. A still further object is to provide a hood catch which will effectually hold the hood downwardly and inwardly.

With the above and other objects in view an embodiment of my invention is shown in the accompanying drawing, and this embodiment will be hereinafter more fully described with reference thereto and the invention will be finally pointed out in the claims.

In the drawing:

Fig. 1 is a horizontal sectional view through the hood and frame and showing the catch in plan, the same being in its operative position,

and intermediate portions of the hood and rock-shafts being broken away.

Fig. 2 is an interior elevation, also in operative position.

Fig. 3 is a vertical sectional view taken along the line 3—3 of Fig. 2.

Fig. 4 is an interior elevation showing the catch in inoperative position, the keeper means not being shown.

Similar reference characters indicate corresponding parts throughout the several figures of the drawing.

Referring to the drawing, the automobile hood 10 is adapted to close in the usual manner against the lacings 11 and 12 of the radiator frame 13 and cowl portion 14 of the chassis.

Upon the inner face of the hood, and preferably at a central point between the hood ends, there is riveted, or otherwise suitably secured, a bracket plate 15 having a pressed up circular bearing boss 16 provided with a central aperture 17 in alignment with an aperture 18 in the hood. A shouldered cylindrical bearing bushing 19 is secured within the aperture 17 as by swaging over, as at 20, and projects into the aperture 18 in the hood so that it is slightly outside the hood surface to form a suitable bearing for the rotary operating handle, presently to be described. The boss is preferably dished, as at 21, in surrounding relation to the aperture 17.

The handle 22 is provided with a reduced diameter shaft 23 which is journaled in the bushing 19, and at its inner end is projected inwardly from the bushing and is provided with shouldered flat surfaces 24—24 at opposed sides, and upon which the barrel cam member is rigidly secured, as will presently more fully appear.

The barrel cam member is preferably in the form of a sheet metal cup having a base 25 and a cylindrical cam wall 26, the base having an eccentrically disposed aperture 27 corresponding in shape to the flattened end of the operating handle shaft 23, and which is engaged upon said shaft end against the shoulders formed by the flat surfaces 24—24 and secured by a washer 28 and a headed screw 29 screwed into a threaded hole 30 in the end of the shaft 23, this assembly at the same time retaining the handle in its bearing.

A pair of rock shafts 31 and 32 are provided upon the interior of the hood extending at each side of the bracket plate 15, being journaled near their inner ends in bearing brackets 33 and 34, preferably curled from the bracket plate 15, and journaled near their outer ends in bearing brackets 35 and 36 secured interiorly to the hood.

The rock-shafts are bent at their inner end extremities to provide offset crank ends 37 and 38, preferably disposed parallel to the rock shafts, and at their outer extremities are bent to provide 5 U-shape offset crank ends 39 and 40, the offset of these crank ends being relatively greater than that of the crank ends 37 and 38 and also being angularly offset with respect to said crank ends 37 and 38.

10 The crank ends 37 and 38 are loosely engaged in the socket ends 41 and 42 of a coupling yoke member 43 of generally oval shape having a flange 44 engaging the barrel cam 25, the latter being disposed in the opening of the yoke member. It 15 will be observed that the flange 26 of the cam member is wider than the flange 44 of the yoke member to allow the latter to slide transversely of the cam member as the same is moved into its operative and inoperative positions.

20 In order to swing the yoke member between its operative and inoperative positions the handle 22 and the cam carried thereby are adapted to be reciprocatingly moved through 180°, and to this end the yoke member is extended at one side of 25 the cam member to allow for the eccentric throw of the latter. In the operative position illustrated in Fig. 2 the cam is swung upwardly and is adapted to be yieldably retained. For this purpose the flange 26 is provided with a flat surface 45 which 30 engages a flat surface 46 at the upper side of the flange 44 in vertical alignment with the axis of the cam, a clearance being provided at the bottom to enable the cam to clear the flat surface 45 as it is rotated, the yoke having a slight upward movement as the cam is disengaged from the detent. It will be understood that in the 35 operative position the rock shaft 31 and 32 are under tension and exert a downward spring pressure on the yoke member, so that the detent is yieldably held in position. In the inoperative position illustrated in Fig. 4 the flat 45 of the cam abuts a stop 47 formed on the lower side of the yoke flange 44 and which limits the counter-clockwise rotation of the cam to 180°. In this 40 position the flat 46 is engaged by the cylindrical surface of the cam so that through friction and the weight of the handle and catch means the parts will be retained in this position.

45 The crank ends 39 and 40 of the respective rock shafts 31 and 32 are adapted to engage angular keeper brackets 48 and 49, suitably mounted on the radiator frame and cowl, or upon any other convenient part of the chassis in proximity to the hood ends. These brackets are illustrated as 50 formed of sheet metal, and their engaging faces, which are preferably disposed at an angle of about 45°, are respectively provided with pressed out rounded ribs 50 and 51 for engagement by the rounded crank ends, this arrangement providing 55 positive and firm engagement, irrespective of variations in the mounting and disposition of the parts.

60 The crank shafts are formed of a suitable spring metal so that the crank ends 39 and 40 may be sprung to a different angular relation to the crank ends 37 and 38 under the torsion and tensional effect of the rock shafts. As above pointed out the crank ends 37 and 38 loosely engage the 65 socket ends 41 and 42 of the coupling yoke member, so that they not only rotate therein but may have a differential movement, in which case the coupling yoke member will assume a position slightly out of parallel with the hood, the play provided between the cam and yoke member 70 being such as to permit this.

The operation is as follows:—

As shown in Fig. 4 the hood catch is in its inoperative or released position, the crank ends 39 and 40 in this case depending so that they clear the keeper brackets as the hood is closed against the lacings. As the handle 22 and cam 26 are swung through 180° from the position shown in Fig. 4 to that shown in Figs. 1, 2 and 3 the yoke member, while remaining in a vertical position, is 80 swung upwardly in an arc about the axis of the crank shafts 31 and 32, thus rotating said crank shafts. As the crank shafts are turned the crank ends 39 and 40 are first brought under and into engagement with the keeper brackets, whereupon 85 they are sprung under tension as the movement of the handle is completed and the flat surface 45 of the cam 26 engages the flat detent surface 46, in which position the parts are held under the tension of the crank shafts. The hood is thus 90 effectually held downwardly and inwardly through the angularity of the keeper brackets. The dot-and-dash lines, Fig. 3, indicate the untensioned angular position of the crank ends 39 and 40 with respect to the crank ends 37 and 38.

95 In the event that any irregularity in the hood, or in the mounting of the keeper brackets, or in the independently formed rock-shafts, causes one of the crank ends to be engaged before the other the loose connection of the rock shafts with the coupling yoke member is such that tension 100 will not be applied to this crank end until the other crank end engages its keeper bracket, whereupon tension will be applied equally to the two crank ends irrespective of such irregularity, and the hood will be held with the same pressure 105 at one end as at the other. The coupling yoke member thus functions as an equalizer between the two rock-shafts.

110 I have illustrated and described a preferred and satisfactory embodiment of my invention, but it will be obvious that changes may be made therein, within the spirit and scope thereof, as defined in the appended claims.

115 Having thus described my invention, what I claim and desire to secure by Letters Patent is:—

120 1. A hood catch actuator, for operating keeper engaging catch means, a movement translating elongated yoke member adapted to be movably connected to said catch means, operating handle means rotatable about an axis transverse to the hood surface, and cam means carried by said handle means engaging said yoke member and adapted to move said member in an up and down direction relative to the hood and whereby said catch means is adapted to be moved into and out of keeper engaging relation.

125 2. A hood catch actuator, for operating keeper engaging catch means, adapted to swing about a horizontal axis parallel to the hood, comprising a movement translating elongated yoke member adapted to be pivotally connected to said catch means, operating handle means rotatable about an axis transverse to the hood surface, and cam means carried by said handle means engaging said yoke member and adapted to move said member in an up and down direction relative to the hood and whereby said catch means is adapted 130 to be moved into and out of keeper engaging relation.

135 3. A hood catch actuator, for operating keeper engaging catch means, comprising movement translating means adapted to be movably connected to said catch means, operating handle means rotatable about an axis transverse to the hood surface, and cam means carried by said 140

145 150

handle means engaging said movement translating means and said cam means adapted to yieldably retain the catch means in its operative position.
6 whereby said catch means is adapted to be moved into and out of keeper engaging relation and
detent means cooperating between said move-
